(No Model.)

A. F. PARKHURST.
BOTTLE STOPPER FASTENER.

No. 319,504.

Patented June 9, 1885.

Wm. J. Littell.

UNITED STATES PATENT OFFICE.

AMOS FREEMAN PARKHURST, OF KEWANEE, ILLINOIS.

BOTTLE-STOPPER FASTENER.

SPECIFICATION forming part of Letters Patent No. 319,504, dated June 9, 1885.

Application filed February 27, 1885. (No model.)

To all whom it may concern:

Be it known that I, AMOS F. PARKHUST, a citizen of the United States, residing at Kewanee, in the county of Henry and State of Illinois, have invented certain new and useful Improvements in Bottle-Stopper Fasteners; and I do hereby declare that the following is a full, clear, and exact description of the invention, which will enable others skilled in the art to which it appertains to make and use the same.

This invention relates to bottle - stopper fasteners; and its object is to provide a simple and improved device of this class which will possess advantages in point of inexpensiveness, durability, ease of operation, and general efficiency.

In the drawings, Figure 1 is a perspective view showing my improved fastener in position for retaining the cork or stopper. Fig. 2 is a corresponding view showing the fastener thrown back to permit withdrawal of the stopper. Fig. 3 is a vertical transverse sectional view. Fig. 4 is a vertical transverse sectional view taken on a plane passing through the bearing of the eccentric. Fig. 5 is a detail perspective view of the eccentric.

Corresponding parts in the figures are denoted by the same letters of reference.

Referring to the drawings, A designates the neck of the bottle, and B the cork or stopper. Around the neck of the bottle is secured a wire loop or collar, C, bent to form two eyes or loops, c c, disposed one at each side and forming bearings for the yoke which carries the eccentric. This yoke D is preferably formed of a single piece of wire, and comprises two downwardly-extending arms, d d, having their lower ends turned inwardly, as shown at d², and then turned outwardly and passed through the eyes c c. At the top end of these arms the wire is bent to form an eye or loop, d³, the latter being connected by a cross-piece, d⁴, formed by the central portion of the wire of which the yoke is bent or constructed.

E designates the eccentric, which consists of a transverse eccentric, e, and a thumb-piece extending therefrom, as shown at e². The eccentric e is provided with cylindrical

ends e³ e⁴, which project through the eyes d³ d⁴, and bear therein during the operation of the eccentric.

A shoulder, e⁴, is formed by the eccentric at each end, and these shoulders serve to obviate or prevent lateral displacement of the eccentric in its bearings.

The handle or thumb - piece e² preferably consists of a curved eccentric portion disposed around the center of the transverse eccentric-shaft E, and set in position in a groove or recess, e⁵, in said eccentric-shaft. This groove retains the thumb-piece e² from lateral displacement, and is preferably dovetailed to receive the corresponding portion of the thumb-piece, as shown at e⁶, whereby the attachment of the handle portion to the part e is firmly secured. The handle portion is curved outwardly and downwardly so as to project over the stopper, and this flattened portion projects outwardly to facilitate the engagement by the thumb or fingers in operating the device.

The operation and advantages of my invention will be readily understood by those skilled in the art to which it appertains.

To fasten the cork or stopper of a bottle, the yoke has simply to be turned in its bearings until the eccentric is brought over the top of the cork or stopper, when, by depressing the handle of the eccentric to the position illustrated in full lines, Fig. 3, the eccentric is caused to firmly clamp or bind the cork and retain it securely in position.

The device may be as readily and conveniently operated to release it from engagement of the cork and permit withdrawal of the latter.

I claim as my invention and desire to secure by Letters Patent—

1. A stopper-fastener comprising the yoke D having loops d³ and arms d pivoted to the neck of the bottle, the eccentric-shaft journaled in said loops d³, and a thumb-piece secured to said eccentric-shaft, substantially as described.

2. The combination, with arms d, pivoted to the neck of the bottle, having loops d³, of the shaft E, the eccentric entirely across the opening in the bottle, and a thumb-piece se-

cured to said shaft for operating the same, substantially as described.

3. The combination, with the collar C, secured around the neck of the bottle, of the yoke D, having loops d^a and arms d pivoted to said collar, the eccentric-shaft journaled in said loops, and a thumb-piece secured to said eccentric-shaft, substantially as described.

In testimony whereof I affix my signature in presence of two witnesses.

AMOS FREEMAN PARKHURST.
